United States Patent Office

Des. 220,864
Patented June 8, 1971

220,864

DUAL BOTTLE UNIT

Richard L. Weckman, Perrysburg, Ohio, assignor to Owens-Illinois, Inc., Toledo, Ohio

Filed Apr. 13, 1970, Ser. No. 22,383

Term of patent 14 years

Int. Cl. D9—01

U.S. Cl. D9—18

FIG. 1

Des. 220,864

PAGE 2

FIG. 5

FIG. 2

FIG. 3

FIG. 4

FIG. 1 is a perspective view of a dual bottle unit showing my new design;

FIG. 2 is a front elevational view thereof;

FIG. 3 is an end view taken from the left end of FIG. 2;

FIG. 4 is an end view taken from the right end of FIG. 2;

FIG. 5 is a top plan view thereof.

I claim:

The ornamental design for a dual bottle unit, substantially as shown and described.
